UNITED STATES PATENT OFFICE.

EMIL DIEBITSCH, OF NUTLEY, NEW JERSEY.

BUILDING TUNNELS.

1,183,352.

Specification of Letters Patent. Patented May 16, 1916.

Application filed April 4, 1914. Serial No. 829,445.

To all whom it may concern:

Be it known that I, EMIL DIEBITSCH, a citizen of the United States, residing in Nutley, New Jersey, have invented certain new and useful Improvements in Building Tunnels, of which the following is a specification.

This invention aims to provide an economical and safe method of building tunnels, adapted especially for submarine tunnels, and especially for such tunnels as have to pass partly through earth and partly through rock, which are not located very far below the bottom of the river, like some of the tunnels built under the East river at the city of New York.

The accompanying drawings illustrate a complete process embodying several features of novelty which are defined in the claims hereinafter and which are capable of separate application under various conditions.

The work is carried on by means of an apparatus or structure which I call a pneumatic caisson but which in its preferred form differs in several respects from the ordinary pneumatic caisson,—notably in that it extends for its full cross-section clear above the surface of the water and is adapted to carry on its own decks most or all of the machinery used so as to constitute a practically self-contained equipment, in that it has chambers for fixed ballast and for water ballast which can be pumped out to lift it and shift it to another point and then restored to sink it, and in that it forms no part of the finished structure.

Figure 1 is a longitudinal section through the caisson in place for the building of the first section of the tunnel, showing the excavation through mud, sand, gravel or other soft material to the bed upon which the tunnel is to rest, at the right hand of the figure, and showing the excavation down to the rock at the left hand; Fig. 2 is a similar view showing the caisson advanced to the end of a completed section of the tunnel in position to commence work on the next section; Fig. 3 is a similar view showing the excavation completed, an invert of concrete built therein and a section of tunnel lining in place in the working chamber ready to be lowered upon the invert; Fig. 3^a is a horizontal section on the line 3^a—3^a of Fig. 3; Fig. 4 is a transverse section midway of the length showing the excavation partly

through rock and partly through mud; Fig. 5 is a similar view showing the excavation where there is no rock, but only mud; Fig. 6 is a section on the line 6—6 (Fig. 3) showing the later stage of the operations in which the invert is completed ready to receive the tunnel lining, and showing the design of the gate at one end of the working chamber; Fig. 7 is a similar view showing the invert, lining and roof complete; Fig. 8 is a horizontal section through the working chamber approximately on the line 8—8 of Fig. 3; Fig. 9 is an enlarged plan view on the same plane showing the head of the sheet piles after driving; Fig. 10 is a plan, Fig. 11 a vertical section and Fig. 12 an enlarged detail in vertical section, illustrating another style of apparatus and method by which the tunnel lining can be introduced.

Referring now to the embodiment of the invention illustrated, the caisson has an upper deck A, a lower machinery deck B and a working chamber C, the deck or roof D of which is sufficiently high above the cutting edge to provide a space free of cross bracing for the introduction of large built up portions of the tunnel as hereinafter described and to permit various other operations to be carried on easily. Any number of shafts E with air locks F on their upper ends are provided for giving access to men and materials to the working chamber. The usual or suitable ballast chambers are provided into and out of which water can be pumped to lower and raise the caisson. The usual air compressors and other machinery may be carried on the machinery deck B so that the whole apparatus is self-contained. In Fig. 1 iron ballast G is shown between the plates H, H' of the double wall which surrounds the working chamber. Besides the openings through air locks and shafts for the passage of men and materials while working under air pressure, one or more special openings into the working chamber are provided for the admission of large sections of the tunnel or tunnel lining, with means for keeping these openings covered while working under air pressure. For example, in the construction of Figs. 1, 2 and 3 an opening is provided at one end of the chamber. The passage J is traversed by a gate or dam K of a style commonly used for closing the entrances of dry docks guided in suitable grooves K' and K² in the sides

and bottom of the passage, which grooves are lined with strips K^3 of rubber or similar packing material backed by timbers K^4 . The gate fits loosely between the packing strips as shown in dotted lines, Fig. 3^a, except when an unbalanced pressure forces it against one or the other of the strips, when it makes a tight joint. In ordinary operation the air pressure forces the gate against the strips K^3 at the outer sides of the grooves. By releasing the pressure the gate is permitted to move upward into a recess L in the upper part of the caisson. It is lifted and lowered by any suitable mechanism such for example as a hydraulic lift cylinder L' extending above the upper deck and carrying a piston whose rod L^2 is connected to the top of the gate. The lower edges of the recess L are also lined with packing strips L^3 .

The character of the bottom is indicated in Fig. 1. It consists in part of mud, sand or gravel M and in part of rock N sloping off into the mud, sometimes entirely below the level of the bottom of the tunnel as at the right hand of Fig. 1, sometimes extending above the top of the intended tunnel as at the left hand of Fig. 1 and sometimes projecting only partly into the space to be occupied by the tunnel as in the right hand portion of Fig. 2. The roof of the tunnel, in the case assumed, is only a few feet below the bottom of the river. I propose, therefore, by means of a dredge to excavate a trench roughly in the mud of the river bottom to an approximately level bearing for the edge of the caisson. The sides of such a trench are indicated at O . See especially Fig. 7. When this has been done the caisson is lowered upon the bottom of the trench with one end at approximately the point where the rock N passes above the bottom of the trench as shown in Fig. 1. For the case of the East river, above referred to, extreme high water is indicated by the letters EHW and mean low water by the letters MLW and the caisson extends at least forty-five feet below extreme low water, this being the distance permitted between the top of the tunnel and extreme low water. The working chamber must be large enough in length and breadth to build a substantial section of the tunnel at one operation, say one hundred feet long and forty feet wide where two tunnel tubes are to be built together. The working chamber must also be high enough to give head room for placing and driving piles. For a tunnel twenty-five feet from top to bottom the sheet piles must be at least the same length and the height of the working chamber must be slightly greater. Having sunk the caisson at the point indicated the air pressure is applied and the excavation is proceeded with in the usual way, excavated material

being taken out through the shafts and locks. In order to hold up the sides while the excavation is proceeding sheet piles P are driven from within the working chamber, taking care to keep the sheeting below the excavation and bracing it wherever necessary by cross braces P' . The sheet piles are driven to or slightly below the level of the bottom of the tunnel, or to rock where the latter projects above such level. These piles are made as nearly air tight as possible.

In the case illustrated the tunnel is to be built entirely below the cutting edge or lower edge of the caisson. In other cases it may be preferable to locate the cutting edge at a level between the top and the bottom of the tunnel so that the latter when completed will project upward into the caisson. The excavation in the latter case

will extend below the cutting edge for a distance equal to only a part of the height of the tunnel. Where the excavation below the cutting edge is of considerable depth it is impossible to balance the pressures upon the opposite faces of the piles. The pressure of air within the excavation is practically uniform from top to bottom, the weight of the air being negligible; but the pressure of water or mud against the outer faces of the piles varies by about four-tenths of a pound per square inch for each vertical foot of distance. For a twenty-five foot excavation for example there would be a difference of ten pounds per square inch between the pressure at the top and that at the bottom.

It is impossible, therefore, to have an evenly balanced pressure on both sides of the piles. I propose to use a pressure of air equal to or slightly greater than the hydrostatic pressure at the bottom. Under such circumstances there is tendency for the air to leak out wherever possible and especially in the upper part of the excavation. If there should be a large number of openings, even though each is small, the leakage would be considerable.

In such a case I propose to limit or prevent the loss of air by covering the small openings through which the leaks take place with sheets of paper, felt or other substantially impervious material. Such sheets are shown at Q in Fig. 5 laid against the face of the piling.

The sheets must be first pasted upon the face of the piling to hold them in place temporarily. The excess of internal pressure will hold them in place permanently. It is not essential that the sheets cover all the openings and stop all possible leaks.

The covering may be applied to a greater or less extent according to circumstances. When the excavation has been carried to a greater depth at one end of the working chamber than at the other end similar impervious sheets may be laid directly upon the bottom at the points where it is higher

100

115
120
125
130

so as to limit or prevent the loss of air through the material at the bottom of such high points where it is unprotected by pil-
ing.

5 Supposing the excavation of mud completed as in Fig. 1, I may make this a start-
ing point for tunneling through the rock N, thus saving the large expense of previous operations in which the tunnel has been
10 started from one of the ends, the excavated material being transported back to the start-
ing point for the entire length of rock tun-
neling, and a shield being carried through
15 the rock because of the necessity of using it
where the rock disappears and mud is en-
countered. As shown in Fig. 1, I propose to
first seal the joint between the rock and the
20 cutting edge at one end of the caisson by
dumping a clay filling R at this point. Then
from within the caisson I first remove the
portion of the rock which lies below the
25 working chamber and then tunnel through
the rock in any usual or suitable way, re-
moving the rock as it is excavated through
the working chamber and the air locks un-
til the tunnel has been extended nearly
30 through the rock to the next section in
which mud is encountered, or entirely
through the rock to the shore end, if the
35 rock extends continuously. Having com-
pleted the excavation, as in Fig. 4 or in Fig.
5, the tunnel is to be built therein. The
method of such building will depend largely
40 upon the design of the tunnel. I have sup-
posed a twin tunnel with a lining of iron or
steel tubing surrounded by a considerable
thickness of concrete. Other constructions,
however, may be used. For example, espe-
cially in the case of a single tunnel, the usual
45 cast iron segments may be used to build up
the lining. For building tunnels with a con-
crete shell and a metal lining the first step
is to lay an invert S of concrete (Fig. 6) in
the bottom of the excavation, constituting
50 approximately the lower half of the shell.
In advance of laying the invert S, piling S'
as indicated in Fig. 3 may be driven, the
heads of the piles being cut off at such a
55 point as to support the invert which is then
laid thereon. Such a piling support is
looked upon with favor by some engineers
in soft material. Various other systems for
supporting the tunnel may be carried on in
60 the working chamber, my invention provid-
ing facilities for a great variety of systems
or designs. Ordinarily, however, it would
be sufficient to lay the invert directly on the
65 mud. The lining is then laid on this invert
and a roof or cover T of concrete (Fig. 7)
laid on the top of the lining.
Where the tunnel lining is to be of cast
70 segments these segments may be introduced
through the air locks and shafts and as-
sembled in place on the supporting invert.
75 Similarly sheet steel or iron linings may be
introduced in small sections through the air
locks and riveted together into a built up
lining in the working chamber. It may be
preferable, however, where the sheet steel
lining is to be used, to rivet the parts to-
78 gether into sections of too great size to be
introduced through the locks. Such sec-
tions may be introduced by providing a
large opening from the outside directly
into the working chamber, such for example
80 as the opening or passage J above referred
to in one end wall; or an opening through
the roof as hereinafter described in con-
nection with Figs. 10, 11 and 12. Referring
first to the construction of Fig. 3 I take a
suitable length of built up sheet steel tubing,
say fifty or one hundred feet thereof, close
the ends and sink such portion alongside the
end of the caisson and parallel with the line
of the tunnel, an indicated at U in dotted
85 lines. The buoyancy of this lining section is
ordinarily sufficient to float it. In case of
necessity buoyant tanks or "floats" may be
attached thereto to bring it to the correct
weight. Thereafter by pumping water into
90 and out of the lining section or the attached
floats I can sink the same to the depth de-
sired very accurately. This is a well under-
stood operation and has been successfully
employed in tunnel building. Having the
95 lining section U at the desired location I
let the air out of the caisson and allow the
water to enter. This balances the pressures
on opposite sides of the gate K at the end of
the caisson and allows the latter to be lifted
100 easily into its recess L, thus opening the
gate. The lining section U is then shifted
endwise into the working chamber after
which the gate K is lowered and the air
pressure again put on in the working cham-
105 ber, closing the gate tightly. The lining
section may be pushed into the working
chamber from the outside or it may be
pulled in by means of cables passing from
the deck down into the working chamber
110 and around guide pulleys and carried
through the passage J by divers and at-
tached to the forward end of the tunnel
section. Or a combination of these two
methods, or in fact various other methods,
115 may be used for introducing the lining sec-
tion into the working chamber. After
closing the gate the compressed air is first
introduced only sufficiently to force out
part of the water to enable workmen to en-
120 ter the chamber and secure the lining sec-
tion to traveling blocks or cranes or similar
supporting means fastened to the ceiling of
the working chamber. The water can then
be forced out entirely and the lining section
125 carefully lowered into its proper place on
the invert and its rear end bolted or other-
wise attached to the forward end of the com-
pleted section U'. In order to open the gate
K promptly I may provide small flooding
130

- gates or valves by which the working chamber can be quickly filled with water when the air pressure is withdrawn so as to quickly counterbalance the pressures on opposite faces of the gate. When the gate is closed and the water is to be expelled I may assist the operation by centrifugal pumps of large capacity working in combination with the air pressure.
- 10 Instead of making an end of the working chamber open I may provide one or more passages directly from the working chamber to the outside through the roof, such for example, as the passage *b*, Fig. 11, which 15 is cut through the deck *D* of the working chamber and through the machinery deck *B*, and which is provided at the level of the main deck *A* with a removable cover *c*. This passage *b* is shown as extending 20 through the full width of the working chamber and extending lengthwise between deep girders *d* adjacent to two of the smaller air locked passages *E*. The cover, indicated as a whole by the letter *c*, consists, as shown 25 in detail in Fig. 12, of a heavy plate *e* stiffened or braced by longitudinal I-beams *f*. The plate rests on gaskets *g* on the tops of the girders *d* and is held down by bolts *h* at intervals hooked under or otherwise fastened to the girders *d*, extending upward between a pair of the I-beams *f* and carrying at its upper end a washer *i* large enough to rest firmly on the two I-beams, and a heavy nut *j* by which the cover can be clamped 30 down on the girders. The nuts *j* may be provided with large enough wings to operate them directly or may be operated by means of wrenches or other tools. One or more openings like *b* with covers *c* may be 35 provided. Ordinarily one would be all that is needed and the cover may be made in sections or in a unit as illustrated. When the cover *c* is removed, the air being first let out of the caisson, a portion of the tunnel 40 or a built up section of the tunnel lining equal in width to the working chamber and in length to a substantial part thereof may be let down and slung in the working chamber in the manner of the lining section *U* of 45 Fig. 3. Or the length of the lining section and the location of the cross braces *P'* may be such as to permit the lining section to be lowered clear down to position on the invert. Or the cross braces *P'* may be removed, the lower ends of the piles being 50 supported on their inner faces by means of the completed invert and the upper ends being never subjected for any length of time to severe inward pressure and being 55 held by their guides in the working chamber; in which case, of course, the section of the tunnel lining may be lowered without chance of interference from the cross braces. After the tunnel lining section is lowered 60 into the working chamber the cover *c* will

be replaced, air pressure applied and water removed and the workmen will re-enter the chamber and set the tunnel lining exactly in place and fasten it to the previously completed section. This operation may be repeated several times without shifting the caisson where the length of completed lining section introduced is only a fraction the length of the working chamber, or the caisson may be shifted between each of the successive operations of introducing a section of the lining; the concrete arch, of course, being laid over the lining before shifting the caisson. The lining being in place and the concrete arch or roof being completed over it the next step is to shift the caisson. For this purpose a portion of the ballast is removed so that the caisson is lightened and is lifted by its buoyancy slightly above the top of the completed portion of the tunnel. Where the tunnel is entirely below the cutting edge, as in the case illustrated, the caisson needs to be lifted only a few inches. Where the tunnel is built partly below the caisson and partly within the working chamber, the caisson, of course, must be lifted a corresponding height. It is then transported lengthwise along the preliminary excavation *O*. Various known means may be used for guiding the caisson during such movement and for shifting it. The completed end of the tunnel may provide a suitable fixed abutment for securing a purchase to shift the caisson longitudinally, such a shifting scheme being indicated diagrammatically in Fig. 2 by a cable *V* attached to the completed end of the tunnel and running over a block fastened to the inner face of the rear end of the tunnel. Other schemes of the same sort may be used. Or where it is undesirable to put any such strains on the tunnel tow boats or the like may be applied on the outside to draw the caisson along. When the rear end of the caisson is located over the completed end of the tunnel more ballast is introduced and the caisson is again sunk to a bearing, when the previous operations are repeated. Before shifting the caisson from one section of the work to the next the sheet piles will generally be withdrawn and held in the working chamber at a suitable elevation to clear the cutting edge and ready for the operation on the next section. Or the sheet piling can be cut off at a point above the excavation where the difficulty of pulling it out is too great.

The sheet piling can be of various constructions as well as the means for guiding and driving them. A specially strong construction, to enable them to withstand great pressure and to make them as nearly airtight as possible, is illustrated in Fig. 9. Each pile in this construction comprises a pair of

timbers W fastened by means of bolts X to opposite faces of an I-beam Y of considerable depth. The flanges Z of the I-beams are exposed, the timber being cut away 5 around such flanges, and are embraced by steel guides a which are fastened to the inner wall plate H of the working chamber.

In tunneling from the caisson into the rock, as soon as the heading has been sufficiently advanced toward the shore to determine that the tunnel can be driven without the use of compressed air it will probably be more economical to close the tunnel end with a bulkhead and to drive the balance of the 10 tunnel from a shaft on the shore by known methods. If either shore end of the tunnel is not in rock, but in mud, sand or gravel the portion built in accordance with this invention under the river may be continued under 15 the shore by means of shields. Such shields can be set up in the working chamber, located as nearly as expedient to the bulkhead line and advanced under the land, using the caisson as a shaft for the passage of men 20 and materials.

In operating my improved apparatus it is advisable that, after transportation to a given point, sufficient water ballast be introduced to sink it to the desired level and a 30 certain additional amount of ballast to hold it firmly on the river bottom under the heaviest air pressure needed for the conduct of the work. The operations of moving and sinking the caisson should be conducted 35 during periods of slack water when there is little or no current. In the case of ordinary currents there will be no substantial difficulty in controlling the caisson by means of hawsers leading to anchors placed up stream.

40 The sheet piling acts chiefly as a diaphragm between the air pressure within and the hydrostatic pressure without, serving to distribute the comparatively small inequalities of pressure between the two opposing 45 forces. It should be made stiff enough and strong enough to take the calculated pressure per square inch over the space of from six to ten square feet in order to take care of soft spots in the mud, or blow holes 50 or cavities caused by dredging which may exist in the banks against which the sheeting bears. When the caisson is located over a rock bottom the sheeting is driven to the rock so as to make a tight connection there- 55 with and is braced across. This will practically exclude water, or will cut the inflow of water down to a point where it can be taken care of by pumps and the air pressure in the trench may be reduced to atmos- 60 pheric pressure. In such circumstances the air locks may be removed or covers such as shown at c may be lifted and the work carried on as in an open cofferdam with great 65 expedition. The style of apparatus with its large working chamber from which the

driving of piles and various other operations can be carried on as described lends itself in fact to a great variety of operations and to the adopting of very useful expedients in accordance with the character of the bottom 70 and other conditions which may be encountered and which may differ from point to point along the length of the tunnel.

As compared with the ordinary shield method, especially where the shield is covered by a comparatively shallow layer of mud, the present process is very much safer for workmen. In shields with vertical working faces the unbalanced pressures at the top and bottom frequently result in 75 blow-outs with loss of air and danger to the work and sometimes with death to the workmen. The present invention permits also of constructing the work from the outside as well as from the inside so that the resulting 80 structure of steel lining and surrounding concrete is better in every respect than the ordinary construction built by the shield method of thousands of cast iron plates with a corresponding number of joints and bolts, 85

the whole laid directly on the mud of the river bottom. With my improved method the bottom can be inspected and reinforced with piling or otherwise if necessary before the actual tunnel is constructed. Every step 90 of construction can be done under complete inspection and with comparative ease and accuracy. For reasons above stated a certain amount of cover is necessary to operate shields, and tunnels built by means of 95 shields must be located comparatively deeply below the river bed; whereas with this invention the tunnel can be built at the minimum depth allowable by harbor regulations 100 below the surface of the river. Also with 105 this invention the labor and handling of materials can be accomplished more economically. There is a saving in the total cost of plant and operation. The apparatus resting on the river bed provides a stable 110

deck equipped with derrick and practically all the necessary machinery for the handling of materials excavated and for the transferring of materials to or from the apparatus. By providing a large uncovered area for the 115 work a large number of men can be employed and the work completed quickly and economically. The progress of the work is not liable to the interruptions from blow-outs and other accidents which often occur 120 with shields. The advantages of the invention are especially noticeable, as compared with the shield method, where the tunnel is located with a shallow over-burden of soil and where the tunnel is to penetrate alternately sand and gravel and then rock and then partly rock and partly sand.

Though I have described with great particularity of detail a certain specific embodiment of my invention yet it is not to be un- 130

derstood therefrom that the invention is restricted to the particular embodiment described. Various modifications thereof in the individual steps of the process and in the combination of steps employed and the order of such steps may be made by those skilled in the art without departing from the invention.

What I claim is—

- 10 1. In the building of a submarine tunnel the method which consists in sinking a pneumatic caisson, excavating under compressed air to a level below the edge of said caisson, and laying in the excavation so formed a tunnel with its top below said edge of the caisson.
- 20 2. In the building of a submarine tunnel the method which consists in sinking a pneumatic caisson, excavating under compressed air to a level below the edge of said caisson and laying in the excavation so formed a tunnel with its top below said edge of the caisson, raising and transporting said caisson to the end of the completed portion of the tunnel and laying an extension of such portion by the same method.
- 30 3. In the building of a submarine tunnel partly through earth and partly through rock the method which consists in sinking a pneumatic caisson with one end located approximately or substantially at the point where the tunnel is to pass from earth to rock, excavating under compressed air from the working chamber of said caisson downward to a level below the edge of said caisson, and extending said excavation horizontally into the rock.
- 40 4. In the building of a submarine tunnel the method which consists in sinking a pneumatic caisson, excavating under compressed air to a level below the edge of said caisson, driving sheet piling from within the working chamber of said caisson to protect the sides of the excavation so formed, and laying a tunnel in said excavation.
- 50 5. In the building of a submarine tunnel the method which consists in sinking a pneumatic caisson, excavating under compressed air to a level below the edge of said caisson, forming a foundation below said level and building on said foundation a tunnel with its top below said edge of the caisson.
- 60 6. In the building of a submarine tunnel the method which consists in sinking a pneumatic caisson, excavating under compressed air to a level below the edge of said caisson, laying a supporting invert of concrete on the bottom of the excavation so formed, laying a tunnel lining of metal on said invert, and laying over said lining a concrete arch, the top of which is below said edge of the caisson.
- 70 7. In the building of a submarine tunnel the method which consists in sinking a pneumatic caisson, excavating under compressed

air from the working chamber of said caisson, laying a portion of a tunnel in the excavation, raising and transporting the caisson to the end of said portion of the tunnel, opening a large passage from said working chamber directly to the outside, and moving a large built-up portion of the tunnel through said passage into the working chamber while the latter is stationary at the end of said completed portion.

75 8. In the building of a submarine tunnel the method which consists in sinking a pneumatic caisson, excavating under compressed air from the working chamber of said caisson, laying a portion of a tunnel in the excavation, raising and transporting the caisson to the end of said portion of the tunnel, opening a large passage from said working chamber directly to the outside, and moving a large built-up portion of the tunnel 80 through said passage into the working chamber while the latter is stationary at the end of said completed portion, and thereafter closing said working chamber, applying air pressure and connecting said built-up portion of the tunnel to said completed portion under compressed air.

90 9. In the building of a submarine tunnel the method which consists in sinking a pneumatic caisson, laying a supporting invert of concrete from within the working chamber of said caisson, opening a large passage from said working chamber directly to the outside and moving a large built-up portion of a tunnel lining through such passage into the working chamber while the latter is stationary over said invert, closing the working chamber and applying air pressure and placing such portion of the lining in position on said invert under compressed air.

95 10. In the building of a submarine tunnel the method which consists in sinking a pneumatic caisson, excavating under compressed air to a level below the edge of said caisson, opening a large passage from said working chamber directly to the outside, introducing a large built-up portion of the tunnel through said working chamber, closing the working chamber, applying air pressure, and laying said portion of the tunnel in said 100 excavation under compressed air.

110 11. In the building of a submarine tunnel the method which consists in sinking a pneumatic caisson, excavating under compressed air to a level below the edge of said caisson, laying a supporting invert of concrete in the excavation so formed, opening a large passage from said working chamber directly to the outside, introducing a large built-up portion of a tunnel lining through such passage into the working chamber, closing the working chamber, and applying air pressure and laying said portion of tunnel lining on said invert and a concrete arch over 115 said lining.

12. In the building of a submarine tunnel the method which consists in sinking a pneumatic caisson, excavating under compressed air to a level below the edge of said caisson, 5 and covering apertures through which air might leak with sheets of fabric which are practically impervious to air.

13. In the building of a submarine tunnel the method which consists in sinking in the 10 river a caisson of sufficient size to permit the introduction of a shield and then tunneling into the shore with such shield, using

said caisson as a shaft from which to start the shield and through which to remove excavated matter and to introduce the necessary materials. 15

In witness whereof, I have hereunto signed my name in the presence of two subscribing witnesses.

EMIL DIEBITSCH.
